GAS-TURBINE

Max Ledinegg, Vienna, Austria, assignor to Simmering-Graz-Pauker Aktiengesellschaft für Maschinen, Kessel- und Waggonbau, Vienna, Austria, a company of Austria

Application December 29, 1951, Serial No. 264,120

Claims priority, application Austria May 28, 1951

8 Claims. (Cl. 253—39.15)

The invention relates to a device for cooling the blades in gas turbines. The cooling is intended primarily for blades subjected to high temperature stressing beyond 700° C. and is effected in a manner known per se by an evaporating liquid, which is caused to circulate by the action of centrifugal force by means of longitudinal bores in the blade.

It is known to associate a common cooling system with all blades. It is also known to associate with each blade a cooler of its own, which is independent of the others and in which the condensation of the vapor formed in the blade is effected. Thereby it is prevented that the whole cooling liquid may flow out upon the leakage of the cooling system even of one blade only, which would result in extensive damage by all blades becoming red hot. On the contrary, the damage is restricted to the one blade concerned. The coolers themselves may be cooled by a secondary medium, water or air. Particularly in the case of cooling by air, large passage cross sections must be provided in the rotor, whereby the construction of the whole turbine is rendered more difficult in particular by the requirement of large rotor diameters.

The further development of the invention consists in that each axial row of blades has associated therewith a heat exchanger, which is independent of the heat exchangers of the other rows of blades. Consequently axial rows of blades can be removed easily together with the heat exchanger. The association of a heat exchanger with an axial row of blades, however, enables also a special construction, which in accordance with the invention consists in that the heat exchangers associated with each row of blades are axially spaced from the blade rings. Therefore it is no longer necessary to conduct the secondary cooling medium axially through the rotor; on the contrary, that medium may be reversed within or behind the sets of coolers so as to emerge at the same end of the rotor body where it is admitted.

In the accompanying drawings,

Fig. 1 shows by way of example an embodiment of the invention in an axial section taken through the upper half thereof, in the case of air being used as a secondary cooling medium,

Fig. 2 is a fragmentary transverse sectional view illustrating a system of detachable units according to the present invention on an enlarged scale,

Fig. 3 shows the arrangement in the case of a liquid secondary cooling medium, particularly water, being used.

In Fig. 1, 1 is the casing of the turbine with the guide blades 5, 2 is the rotor with the rotor blades 11. The hot gases enter at 3 the blade ring formed by the guide and rotor blades, and pass off at 4.

The rotating part is sealed against the casing by the labyrinth packings 20. In order to be cooled each rotor blade has passage means including central bores 13 and a larger number of peripheral bores 12, which communicate with each other at the blade top. In the cen-

2

tral bores the cooler cooling medium, of higher specific gravity, flows outwardly under centrifugal force, is heated or evaporated, and when its specific gravity has thus been reduced the medium is forced inwardly. This cooling cycle does not form part of the invention but has been described only by way of example because other cooling processes may be used without departing from the scope of the invention.

The attachment of the rotor blades to the rotor body is effected by means of fir-cone roots 21 engaging the outer slot portions 25a of slots 25 in the rotor body. Projecting means 25' in the slot portions 25a secure the rotor blades against radial movement. A conduit means 10' is secured to the roots of all rotor blades of each axial row of rotor blades, and is located in the inner slot portion 25b of the respective slot 25. Each conduit means 10' communicates with the passages 12, 13 in the rotor blades of the respective row, and with the passages of a heat exchanger 10 which is secured to the respective conduit means 10' and forms part of the same. The inner portions 25b of slots 25 open into a cavity 14 in Fig. 1 and 14a in Fig. 3. The heat exchangers 10a illustrated in Fig. 3 are smaller than the heat exchangers 10 of the construction of Fig. 1 since the heat exchangers 10 are cooled by air and the heat exchangers 10a are cooled by water as a secondary cooling medium as will be described hereinafter in greater detail.

Each heat exchanger 10 preferably consists of radial tubes having cooling fins and being inserted with the undercut roots 23 thereof into corresponding axially extending grooves 29 which are formed in the cavity 14 of the rotor body.

The cavity 14 shown in Fig. 1 is closed by a means 27 provided with an inlet 31 and an outlet 32, respectively communicating with the inlet 8 and the outlet 9 of the stator 1, and including a partition 24 extending to about the center portions of the heat exchangers 10 so that air can be circulated as a secondary cooling medium through inlets 8 and 31, cavity 14, and outlets 32 and 9. The arrangement shown in Fig. 3 is similar, and a means 27a is provided in the cavity 14a and has an inlet 8 and an outlet 9 for circulating water as a cooling medium through the cavity 14a whereby the heat exchangers 10a are cooled. The means 27a is shown in Fig. 3 to be removable, and to be attached by threaded bolts 28 to the rotor body. The means 27 shown in Fig. 1 is secured in a similar way to the rotor body. The inlets 31 are spaced in circumferential direction from each other, and threaded bolts, not shown in Fig. 1, are located between inlets 31, and extend between the tubes of heat exchangers 10. The end portion of the bolts are threaded into the rotor body as described with reference to Fig. 3.

The stator 1 consists of two halves which are connected to each other by means of flanges 35 and bolts 36. This construction is known, and not an object of the present invention.

It will be understood that each row of rotor blades 11, the conduit means 10' associated with the respective row of rotor blades 11, and the heat exchanger 10 secured to the respective conduit means 10', constitute a detachable unit which is held by root members 21 and 23 in slot portions 25a of slots 25, and in grooves 29, respectively, in such a manner that each unit is axially slid able, but secured by the projecting means 25' against radial movement. Consequently, each unit can be removed in axial direction, and also mounted in axial direction independently of the other units.

In order to remove, or mount, a unit, it is, of course, necessary to first detach the respective stator half, and to withdraw the means 27 or 27a after removing the

bolts 28. The opened cavities 14 and 14a are easily accessible so that each unit can be pulled out independently of the other units.

Due to the fact that part of each conduit means 10', and more particularly the respective associated heat exchangers 10 are all mounted in the same cavity of the rotor body, it is possible to cool all units simultaneously by a common secondary cooling medium which is circulated through inlets 31 or 8, outlets 32 or 9, and the respective cavity 14 of 14a in the rotor body.

I claim:

1. In a gas turbine rotor, in combination, a rotor body having an axis and being formed with a plurality of slots extending in axial direction of said rotor body in the outer surface thereof and with a cavity adapted to receive a secondary cooling medium; a plurality of detachable units, each unit mounted in one of said slots slidable in axial direction so as to permit removal and mounting of each unit in axial direction independently of the other units, each unit including a row of axially spaced rotor blades formed with passage means for a coolant, means securing the respective unit to said rotor body against radial movement, and a conduit means secured to the rotor blades of said row of rotor blades and communicating with said passage means in the associated row of rotor blades so as to permit circulation of a coolant through said conduit means and the rotor blades of the respective unit independently of the other units, a part of said conduit means of each of said detachable units being located in said cavity so as to be cooled by said secondary cooling medium.

2. In a gas turbine rotor, in combination, a rotor body having an axis and being formed with a plurality of slots extending in axial direction of said rotor body in the outer surface thereof and with a cavity adapted to receive a secondary cooling medium; a plurality of detachable units, each unit mounted in one of said slots slidable in axial direction so as to permit removal and mounting of each unit in axial direction independently of the other units, each unit including a row of axially spaced rotor blades formed with passage means for a coolant, means securing the respective unit to said rotor body against radial movement, a conduit means secured to the rotor blades of said row of rotor blades and communicating with said passage means in the associated row of rotor blades, and a heat exchanger communicating with said conduit means so as to permit circulation of a coolant through said heat exchanger, said conduit means and the rotor blades of the respective unit independently of the other units, said heat exchangers of said detachable units being located in said cavity so as to be cooled by said secondary cooling medium.

3. In a gas turbine rotor, in combination, an elongated rotor body having an axis and being formed with a plurality of slots extending in axial direction of said rotor body in the outer surface thereof, and with a cavity located at one end of said rotor body and adapted to receive a secondary cooling medium, a plurality of detachable units, each unit mounted in one of said slots and slidable in axial direction so as to permit removal and mounting of each unit in axial direction independently of the other units, each unit including a row of axially spaced rotor blades mounted in the associated slot formed with passage means for a coolant, means securing the respective unit to said rotor body against radial movement, a conduit means secured to the rotor blades of said row of rotor blades and communicating with said passage means in the associated row of rotor blades, and a heat exchanger spaced in axial direction from said rotor blades and communicating with said conduit means so as to permit circulation of a coolant through said heat exchanger, said conduit means and the rotor blades of the respective unit independently of the other units, said heat exchangers of said detachable units

being located in said cavity so as to be cooled by said secondary cooling medium.

4. In a gas turbine rotor, in combination, a rotor body having an axis and being formed with a cavity; a plurality of detachable units, each unit being mounted on said rotor body slidable in axial direction so as to permit removal and mounting of each unit in axial direction independently of the other units, each unit including an axially extending row of rotor blades formed with passage means for a coolant, means securing the respective unit to said rotor body against radial movement, and a conduit means secured to said rotor blades of said row of rotor blades and communicating with said passage means in the rotor blades of the associated row of rotor blades so as to permit circulation of the coolant through said conduit means and through said passage means in the rotor blades of the respective unit independently of the other units, a part of the conduit means of each of said units being located in said cavity in said rotor body; and means for circulating a secondary cooling medium in said cavity about said part of the conduit means of each unit for cooling said conduit means of all said detachable units.

5. In a gas turbine rotor, in combination, a rotor body having an axis and being formed with a plurality of slots extending in axial direction of said rotor body in the outer surface thereof and with a cavity; a plurality of detachable units, each unit mounted in one of said slots slidable in axial direction so as to permit removal and mounting of each unit in axial direction independently of the other units, each unit including an axially extending row of axially spaced rotor blades formed with passage means for a coolant, means securing the respective unit to said rotor body against radial movement, a conduit means secured to the rotor blades of said row of rotor blades and communicating with said passage means in the rotor blades of the associated row of rotor blades, a heat exchanger secured to the respective conduit means and communicating with said conduit means; and means for circulating a secondary cooling medium in said cavity about said heat exchangers of all said detachable units.

6. In a gas turbine rotor, in combination, a rotor body having an axis and being formed with a plurality of slots extending in axial direction of said rotor body in the outer surface thereof and with a cavity; a plurality of detachable units, each unit mounted in one of said slots slidable in axial direction so as to permit removal and mounting of each unit in axial direction independently of the other units, each unit including an axially extending row of axially spaced rotor blades formed with passage means for a coolant, means securing the respective unit to said rotor body against radial movement, a conduit means secured to the rotor blades of said row of rotor blades and communicating with said passage means in the rotor blades of the associated row of rotor blades, a heat exchanger secured to the respective conduit means and communicating with said conduit means, said heat exchangers being spaced in axial direction from said rotor blades; and means for circulating a secondary cooling medium in said cavity about said heat exchangers of all of said detachable units.

7. In a gas turbine rotor, in combination, a rotor body having an axis and being formed with a plurality of slots extending in axial direction of said rotor body in the outer surface thereof, and with a cavity adjacent one end of said rotor body; a plurality of detachable units, each unit mounted in one of said slots slidable in axial direction so as to permit removal and mounting of each unit in axial direction independently of the other units, each unit including an axially extending row of axially spaced rotor blades formed with passage means for a coolant, means securing the respective unit to said rotor body against radial movement, a conduit means secured to the rotor blades of said row of rotor blades and communicating with said passage means in the rotor blades of the associated row of rotor blades so as to permit circulation of the coolant through said conduit means and through said passage means in the rotor blades of the respective unit independently of the other units, a part of the conduit means of each of said units being located in said cavity in said rotor body; and means for circulating a secondary cooling medium in said cavity about said part of the conduit means of each unit for cooling said conduit means of all said detachable units.

ciated row of rotor blades, a heat exchanger located in said cavity and being secured to the respective conduit means and communicating with said conduit means; and cooling means for circulating a secondary cooling medium through said heat exchangers of all said detachable units and including an axially extending partition located in said cavity so as to define in said cavity an inlet and an outlet for guiding said secondary cooling medium in one axial direction into said cavity and in the opposite axial direction out of said cavity so that said secondary cooling medium is supplied to and discharged from the same side of said heat exchangers.

8. In a gas turbine rotor, in combination, a rotor body having an axis and being formed with a plurality of slots extending in axial direction of said rotor body in the outer surface thereof, and with a cavity located spaced in axial direction from said rotor blades and adjacent one end of said rotor body; a plurality of detachable units, each unit mounted in one of said slots slidable in axial direction so as to permit removal and mounting of each unit in axial direction independently of the other units, each unit including an axially extending row of axially spaced rotor blades formed with passage means for a coolant, means securing the respective unit to said rotor body against radial movement, a conduit means secured to the rotor

10
